Patented Apr. 11, 1922.

UNITED STATES PATENT OFFICE.

LEROY L. RICHARD, OF VISALIA, CALIFORNIA.

AUXILIARY TABLE.

1,412,630.

Specification of Letters Patent. Patented Apr. 11, 1922.

Application filed March 7, 1921. Serial No. 450,292.

To all whom it may concern:

Be it known that I, LEROY L. RICHARD, a citizen of the United States, residing at Visalia, in the county of Tulare and State 5 of California, have invented certain new and useful Improvements in Auxiliary Tables, of which the following is a specification.

My invention relates to that class of table-attachments comprising a supplementary or auxiliary table, relatively small, and adapted to normally lie, when not in use, close up under the main table, and, when required for use to be readily extended therefrom to a lower level, thereby providing for 15 the convenience of children, particularly in refreshment parlors.

The object of my invention is to provide an auxiliary table of this type, simple in construction, cheap to manufacture and of 20 good appearance and which is held, both in its folded and extended positions, with stability and rigidity sufficient for its purpose, without detracting from its ease of operation in throwing it into and out of use.

25 To this end my invention consists in the novel auxiliary table which I shall herein-after fully describe, by reference to the accompanying drawings, in which—

Fig. 1 is a side elevation of my auxiliary 30 table, in its extended position, ready for use, the dotted lines showing its folded position out of use.

Fig. 2 is a part elevation and part section on the line 2—2 of Fig. 1.

35 Fig. 3 is a part plan and part section on the line 3—3 of Fig. 1.

1 indicates the slab or top of the main table and 2 is the shelf constituting the auxiliary table. The auxiliary table may be of 40 any predetermined size and shape, as, for example, as here indicated, a relatively small circular shelf adapted, in its more common use, to hold a refreshment dish or glass; and for this purpose, I have shown it as provided 45 with fixed peripheral confining lugs 3, and an adjustable lug 4, playing in a slot 5 of the shelf, and provided with a shank 6 slidably mounted in guides 7 under the shelf, said shank having an underlying finger-hold 50 8, and a controlling spring 9.

By grasping the finger hold 8, the adjustable lug 4 may readily be moved outwardly to receive the refreshment vessel and when released said lug will move in again, under 55 the tension of the spring, to properly hold said vessel against the fixed lugs 3.

At one side or portion of its rim, the auxiliary table shelf 2 is provided or formed with an angularly rising bracket 10.

11 is a supporting member which has an 60 angularly depressed bracket 12, which when said member is secured under the main table 1, as shown in Fig. 1, lies substantially parallel with the bracket 10 of the auxiliary table-shelf. The supporting hanger for the 65 auxiliary table-shelf comprises a pair of associated links 13 and 14. The link 13 is pivoted above to the bracket 12, at 13' and below, it is pivoted to the bracket 10, at 13''. The link 14 is similarly pivoted to said 70 brackets at 14' and 14'', these connections thus being of the "parallel-ruler" type, enabling the table-shelf 2 to maintain its horizontality in all positions. The links 13 and 14 may assume any shape in cross-section, 75 flat, angular or curved, but in their best form, they are approximately semi-circular with straight edge portions, as seen in Fig. 3, and are associated in interfitting overlapping relation, thereby complementing 80 each other to form a substantially cylindrical column giving strength and rigidity, and having a good appearance. Moreover, this form and association of the links gives opportunity to make their inter-fit some- 85 what close frictionally but without interfering with their relative sliding movement, thereby adding to the general rigidity of the column, in all its movements and positions, and tending to render more certain the lock- 90 ing together of said links against relative movement, in order to hold the table shelf in any of its predetermined positions, as, for example, at the extremes of movement.

The locking is automatic and also is releasable by pressure applied to the auxiliary table-shelf in moving it to and from its positions. Any suitable pressure-yielding latch may be used to releasably lock and hold the two links against relative movement. In the 100 form of links here shown, the latch I prefer comprises a pair of beveled or round ended pins 15 slidably mounted in the lapped portions of the link 13, and yieldingly controlled by a spring 16 within said link, said pins being adapted to engage sockets or holes 17 and 18 in the lapped portions of the link 14, the sockets or holes 17 defining the relative movement of the links when the auxiliary table-shelf is extended for use, as 110 shown by the full lines in Fig. 1, and the sockets or holes 18 defining the limit of move-

ment when the auxiliary table-shelf is folded up under the main table, as shown by the dotted lines in Fig. 1.

In the face of the link 14 is a hole 19 to receive the adjustable lug 4 of the auxiliary table-shelf when the device is folded up, thereby enabling the parts to lie close together.

It will now be seen that if, when the device is in the folded position shown by the dotted lines in Fig. 1, a downward pressure be imposed upon said table—shelf 2 tending to swing the links, the latter by relative movement in opposite directions will break the yielding latch connection at 18 between them; and this movement will continue until as the table reaches its limit of extension as shown by the full lines in Fig. 1, the spring latch pins 15 will enter the sockets 17 and thus lock the links again. Conversely, an upward pressure on the auxiliary table, will reverse the relative link movement, unlocking them at the beginning and relocking them at the end of the folding movement.

I have herein described my device in its preferred form and use; but it is to be understood that its use may be varied to serve the purposes of any folding table-shelf, and its structure may be altered in details of form and shape without departing from the invention as defined by the appended claims.

I claim:—

1. The combination of a shelf; a supporting member; a pair of links pivotally connecting said shelf and member in parallel relation; and means carried and actuated by said links for locking them together against relative movement.

2. The combination of a shelf; a supporting member; a pair of links pivotally connecting said shelf and member in parallel relation; and a pressure-yielding latch carried and actuated by said links for locking them together against relative movement.

3. The combination of a shelf; a supporting member; a pair of links pivotally connecting said shelf and member in parallel relation, said links interfitting in complementary overlapping slidable relation; and means carried by said links for locking them together against relative movement.

4. The combination of a shelf; a supporting member; a pair of links pivotally connecting said shelf and member in parallel relation, said links interfitting in complementary overlapping slidable relation; and a pressure-yielding-latch carried by said links for locking them together against relative movement.

5. The combination of a shelf; a supporting member; a pair of links pivotally connecting said shelf and member in parallel relation, said links interfitting in complementary overlapping slidable relation; and

a pressure-yielding-latch carried by the lapped portions of said links for locking them together against relative movement.

6. The combination of a shelf; a supporting member; a pair of links pivotally connecting said shelf and member in parallel relation, said links interfitting in complementary overlapping slidable relation; a pressure yielding latch pin carried by the lapped portion of one of said links; and sockets in the lapped portion of the other of said links, with which said pins engage, to lock the links together against relative movement.

7. An auxiliary-table comprising a table-shelf having an upwardly inclined bracket; a supporting member adapted for attachment under a main-table, said member having a downwardly inclined bracket; a pair of links pivotally connecting the two brackets in parallel relation; and means carried and actuated by said links for locking them together against relative movement.

8. An auxiliary-table comprising a table-shelf having an upwardly inclined bracket; a supporting member adapted for attachment under a main-table, said member having a downwardly inclined bracket; a pair of links pivotally connecting the two brackets in parallel relation; and a pressure-yielding-latch carried and actuated by said links for locking them together against relative movement.

9. An auxiliary-table comprising a table-shelf having an upwardly inclined bracket; a supporting member adapted for attachment under a main table, said member having a downwardly inclined bracket; a pair of links pivotally connecting the two brackets in parallel relation, said links interfitting in complementary overlapping slidable relation; and a pressure yielding-latch carried by the links for locking them together against relative movement.

10. An auxiliary-table comprising a table-shelf having an upwardly inclined bracket; a supporting member adapted for attachment under a main table, said member having a downwardly inclined bracket; a pair of links pivotally connecting the two brackets in parallel relation, said links interfitting in complementary overlapping slidable relation; and a pressure-yielding-latch carried by the links for locking them together against relative movement at the extremities of their movement about their pivotal connections.

11. An auxiliary-table comprising a table-shelf having an upwardly inclined bracket; a supporting member adapted for attachment under a main table, said member having a downwardly inclined bracket; a pair of links pivotally connecting the two brackets in parallel relation, said links interfitting in

complementary overlapping slidable relation; and a pressure-yielding-latch carried by the links for locking them together against relative movement at the extremities of their movement about their pivotal connection, consisting of a spring controlled beveled pin carried by the lapped portion of

one of said links and sockets in the lapped portion of the other of said links, with which said pin engages.

10

In testimony whereof I have signed my name to this specification.

LERoy L. RICHARD.
